UNITED STATES PATENT OFFICE.

LEWIS E. MACOMBER, OF NEW YORK, N. Y., ASSIGNOR TO SETH THOMAS CLOCK CO., OF THOMASTON, CONNECTICUT, A CORPORATION.

DESIGN FOR A CLOCK CASE.

60,960.

Specification for Design. Patented May 16, 1922.

Application filed February 13, 1922. Serial No. 673. Term of patent 7 years.

To all whom it may concern:

Be it known that I, LEWIS E. MACOMBER, a citizen of the United States, residing at New York, in the county of New York and State of New York, have invented a new, original, and ornamental Design for a Clock Case, of which the following is a specification, reference being had to the accompanying drawing, forming part thereof.

The figure is a perspective view of a clock case showing my new design.

I claim:

The ornamental design for a clock case as shown.

LEWIS E. MACOMBER.

Witness:

B. A. WEATHERS, Jr.
